UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

SHANK AND BIT PUNCH.

1,395,747.

Specification of Letters Patent.

Patented Nov. 1, 1921.

Application filed April 24, 1920. Serial No. 376,306.

To all whom it may concern:

Be it known that I, WILLIAM A. SMITH, a citizen of the United States, residing at Easton, in the county of Northampton and State of Pennsylvania, have invented a certain new and useful Improvement in Shank and Bit Punches, of which the following is a specification.

This invention relates to machines for punching the bits and shanks of hollow drill steels or similar tools, for use more especially during the processes of sharpening and re-shanking the steels, in order to reopen the holes in the bits or shanks to the required extent after the heating and forging operations.

The primary object of the invention is to secure a quick acting machine by means of which a pin may be accurately driven into the hollow steel or tool and withdrawn under complete control of the operator.

Difficulty is sometimes experienced in pushing a pin into a hollow steel or tool, especially at the shank end, which may require deeper punching than the bit end, and an object of the present invention is to enable the pin to be automatically tapped or hammered into the tool or article to be punched by fluid actuated means as the punching mechanism is fed forward, instead of being merely pushed in.

Another object of the invention is to provide manual actuating means for feeding the punching mechanism forward, which may be started and stopped as desired. Any suitable means, as a spring, may be provided for returning the punching mechanism to its initial or starting position upon release of the manual force applied for the forward feeding movement.

Means may also preferably be provided for automatically admitting fluid pressure to the punching mechanism after the forward feeding movement has been started by the manual feeding means and for cutting off said fluid pressure upon the return of the punching mechanism to starting position.

Further objects of the invention will hereinafter appear and to all of these ends the invention consists of the features of construction and combinations of elements described and claimed in this specification and shown in the accompanying drawings in which—

Figure 1 is a side elevation of a bit and

shank punch shown mounted on a drill sharpener for convenience,

Fig. 2 is an enlarged longitudinal sectional elevation of the fluid actuated punching mechanism partly broken away, 60

Fig. 3 is a side elevation of a modified form of mechanism,

Fig. 4 is an enlarged detail view partly in longitudinal section of a pin holder forming an anvil block and means for removably holding a pin in the holder, 65

Fig. 5 is a transverse sectional view on the line 5—5 of Fig. 4 looking in the direction of the arrows,

Fig. 6 is a view similar to Fig. 4 of a 70 modified form of pin holder and anvil block, and

Fig. 7 is a transverse sectional view on the line 7—7 of Fig. 6 looking in the direction of the arrows, 75

The punching machine may be mounted upon a separate pedestal but for convenience the machine is shown attached to a drill sharpener A the outline of which is indicated in dot and dash lines, so that the jaws 80 B and C of the drill sharpener may be utilized for clamping the drill steel D in place during the punching.

As shown in this instance a bracket E is 85 suitably secured to the frame of the drill sharpener A as by means of the bolts F and guiding means preferably in the form of a guide bar G extends horizontally from the bracket E, in convenient position for slidably supporting the fluid actuated punching 90 mechanism opposite the location of the drill steel D or article to be punched.

The punching mechanism forming one element of this invention preferably comprises a percussive tool of the hammer type 95 having a cylinder casing H suitably mounted upon a carriage J slidably supported upon the guide G but held from rotation by a suitable key K. A punch in the form of a pin L is adapted to be tapped or hammered 100 into the drill steel D by blows in one direction of the hammer piston O reciprocating in the cylinder casing H and hammered out of the drill steel by blows of the hammer piston in the opposite direction. Suitable 105 manually actuated means controlled either by the foot or hand of the operator as indicated in Figs. 1 and 3 are preferably provided for bodily feeding the punching mechanism forward as the hammer operates. 110

- Suitable spring actuated means under the chine influence of the spring P may be provided for bodily returning the punching mechanism to initial position as the hammer piston 5 operates, but the invention is not to be understood as limited to spring actuated feed back mechanism, for this is only one convenient method of feeding back. Without the spring P , the entire punching mechanism 10 could be actuated both forward and backward by manual means under direct control of the operator as the hammer piston operates and in some instances, such operation might be preferable.
- 15 The punching mechanism in the form of a percussive tool may be of any suitable or usual construction and in this instance the cylinder casing H is provided with the front head Q , the back head R and the back end 20 portion S , all adapted to be secured together and to the collar T of the carriage J as by means of the side bolts U . A suitable anvil block V has a limited movement within the front head Q and forms a holder for 25 the pin L which may be inserted within the end of the anvil block or holder V and held in place by means of the transverse pin W shown in detail in Figs. 4 and 5. The pin is retained in position by means of a 30 suitable retainer in the form of a circular spring X having apertures in its ends through which the pin passes. In Fig. 2 the anvil block V is shown in its rearward position in the front head Q and in the path 35 of the piston to receive the impact blows.
- In the modification of the pin retaining means shown in Figs. 6 and 7, a short pin Y is held within the pin holder V by means of the spring sleeve Z .
- 40 The percussive tool forming the punching mechanism is constructed in any suitable manner to provide for the distribution of fluid pressure to the portions of the cylinder for actuating the hammer piston O , in 45 this instance fluid pressure being admitted at the inlet a and in the position of the parts shown in Fig. 2 passes through the passage way b and port c , to the forward portion of the cylinder and thence through 50 the port d and passage way e to the rearward portion of the cylinder as indicated by the arrows for operating the piston forward. The rearward portion of the cylinder is exhausted through the exhaust port f and during 55 the operation of the tool constant pressure is maintained on the rearwardly acting surface of the piston formed by the shoulder g forming a cushion on the forward stroke. As the punching mechanism 60 is moved backwardly or retracted along the guide bar G the anvil block V assumes its forward position in the front head out of the path of the piston.
- A spring controlled valve h is preferably 65 provided in the end portion S of the ma-
- Suitable spring actuated means under the chine for automatically controlling the starting and stopping of the piston. This valve is provided with an extension j adapted to bear against the stop k when the punching mechanism is in retracted position, thus automatically shutting off the supply of fluid pressure to the cylinder. After the punching mechanism is moved away from the stop k the valve h automatically opens and the piston is started in 70 operation.
- In Fig. 1 suitable means are shown actuated and controlled by the foot of the operator for moving the punching mechanism forward as the pin L is hammered into the drill 75 steel or article to be punched. Any suitable means may be provided for this purpose and in this instance the bell crank lever o is pivoted at p to the bracket E , one arm of the bell crank lever being connected to the carriage J by the link q , the other arm being connected to a foot lever r by means of the spring pressed rod s sliding within the socket t . A spring u is adapted to be compressed between the flange v on the rod s and the end of the socket t , so that upon pressing down on the outer end of the foot lever r , the bell crank lever o is rocked to feed the punching mechanism forward, and the compression spring u acts to take up the 80 vibration in the links and levers. Upon releasing the pressure applied by the foot of the operator, the retracting spring p returns the punching mechanism to its initial or starting position as the pin L is hammered 85 out of the drill steel.
- In the modification of the invention shown in Fig. 3 hand operated means are provided for feeding the punching mechanism forward. In this instance a rod w is slidably 90 inserted within a sleeve x pivoted at y to the carriage J . The rod w may be provided with a collar z between which and the sleeve x a spring 2 is placed. Another spring 3 is preferably placed between the sleeve x 95 and a nut 4 at the end of the rod w , these springs 2 and 3 being for the purpose of taking up vibration. The rod w is pivoted at 5 to a hand lever 6 which in turn is pivoted at 7 to the bracket E . As 100 the hand lever 6 is pulled forward toward the operator, the punching mechanism is fed forward and upon release of the force supplied by hand, the retracting spring P returns the punching mechanism to its 105 initial or starting position.
- I claim—
1. In a machine for re-opening the bits and shanks of hollow drill steels and similar tools, the combination of means for holding 110 the drill steel, a pin adapted to enter the drill steel, punching mechanism in the form of a fluid actuated hammer tool for hammering the pin into the drill steel, said hammer tool having a reciprocating piston and an 115

- anvil block located at the forward end carrying said pin, and manually actuated means for feeding the punching mechanism forward.
5. 2. In a machine for re-opening the bits and shanks of hollow drill steels and similar tools, the combination of means for holding the drill steel, a pin adapted to enter the drill steel, punching mechanism in the form of a fluid actuated hammer tool for hammering the pin into the drill steel, said hammer tool having a reciprocating piston, an anvil block located at the forward end and having limited longitudinal movement in the tool, said pin being carried by the anvil block, manually actuated means for feeding the punching mechanism forward, and means for returning the punching mechanism as the pin is withdrawn from the drill steel.
10. 3. In a machine for re-opening the bits and shanks of hollow drill steels and similar tools, the combination of means for holding the drill steel, a pin adapted to enter the drill steel, punching mechanism in the form of a fluid actuated hammer tool for hammering the pin into the drill steel, said hammer tool having a reciprocating piston, an anvil block located at the front end and having limited longitudinal movement in the tool, said pin being carried by the anvil block, and manually actuated means for feeding the punching mechanism forward against spring pressure, said spring pressure acting to return the punching mechanism as the pin is withdrawn from the drill steel, when the manual force applied is released.
15. 4. In a machine for re-opening the bits and shanks of hollow drill steels and similar tools, the combination of means for holding the drill steel, a pin adapted to enter the drill steel, punching mechanism in the form of fluid actuated means for hammering the pin into the drill steel, manually actuated means for feeding the punching mechanism forward and automatic means for admitting fluid pressure to the punching mechanism after the feeding movement has been started by the said manual means.
20. 5. In a machine for re-opening the bits and shanks of hollow drill steels and similar tools, the combination of means for holding the drill steel, a pin adapted to enter the drill steel, punching mechanism in the form of fluid actuated means for hammering the pin into the drill steel, manually actuated means for feeding the punching mechanism forward and automatic means for admitting fluid pressure to the punching mechanism after the feeding movement has been started by the said manual means.
25. 6. In a machine for re-opening the bits and shanks of hollow drill steels and similar tools, the combination of means for holding the drill steel, a pin adapted to enter the drill steel, fluid actuated means adapted to hammer the pin into the drill steel by repeated blows in one direction and hammer the pin out of the drill steel by repeated blows in the opposite direction, and manually actuated means for feeding the hammering device lineally forward along the axis of the drill steel.
30. 7. In a machine for re-opening the bits and shanks of hollow drill steels and similar tools, the combination of means for holding the drill steel, a pin adapted to enter the drill steel, fluid actuated means adapted to hammer the pin into the drill steel by repeated blows in one direction and hammer the pin out of the drill steel by repeated blows in the opposite direction, manually actuated devices for feeding the hammering device lineally forward along the axis of the drill steel, and shock absorbing means located between the hammering device and the manually actuated devices to reduce vibration in the said manual devices.
35. 8. In a machine for re-opening the bits and shanks of hollow drill steels and similar tools, the combination of means for holding the drill steel, a pin adapted to enter the drill steel, fluid actuated means adapted to hammer the pin into the drill steel by repeated blows in one direction and hammer the pin out of the drill steel by repeated blows in the opposite direction, manually actuated means for moving the hammering device lineally forward and backward along the axis of the drill steel, and shock absorbing means located between the hammering device and the manually actuated devices for reducing vibration in the said manual devices.

In testimony whereof, I have hereunto set my hand.

WILLIAM A. SMITH.
